UNITED STATES PATENT OFFICE.

JOHN SIVÁK, ALEXANDER NAGY, AND LADISLAUS BANDURAY, OF NEW YORK, N. Y.

TOILET-SEAT COVER.

1,148,867.

Specification of Letters Patent.

Patented Aug. 3, 1915.

Application filed December 28, 1914. Serial No. 879,347.

To all whom it may concern:

Be it known that we, JOHN SIVÁK, a citizen of the United States, and ALEXANDER NAGY and LADISLAUS BANDURAY, subjects of the King of Hungary, all residing at New York, in the county of New York and State of New York, have invented new and useful Improvements in Toilet-Seat Covers, of which the following is a specification.

10 This invention relates to toilet seat covers and is designed to be used in conjunction with our device described in our application for Letters Patent on a hygienic toilet seat, filed July 7, 1914, Serial #849,401. Its object is to provide a device for the protection of toilet seats and especially for such as are covered with paper, from being urinated upon or otherwise soiled or infected while not in use.

20 In the accompanying drawing: Figure 1 is a side elevation of our device applied to a toilet seat. Fig. 2 is a plan view and Fig. 3 a partly sectional, partly elevational view of the same, the latter on an enlarged scale, only a fraction of the device being shown. Fig. 4 is a detail view on an enlarged scale.

Throughout the several views the same reference character is applied to the same part.

30 Referring more particularly to the drawing, 4 is a bowl of a toilet having hinged to its rear end a pair of seat sections 5 connected at the bottom of their fore ends by a tie-member 5^a, covered by a strip of paper each. To the outer longitudinal edges of these seat sections 5 are hinged a pair of covers 6 of the same shape as the seat sections 5, by means of hinges 7, containing springs tending to close the covers 6 down on the seat sections 5.

40 On top of each cover 6 near the outer edges thereof and at about the middle of their length are provided eyelets 8 to which are fastened cords 9 running from the eyelets over a pair of guide rolls 10 mounted on suitable brackets 11. The other ends of the cords 9 are each fastened to one of a pair of rods 12 rigidly attached to a treadle

or bridge 13 placed in front of the bowl 4, slightly slanting from the bowl toward the floor. A pair of springs 14 supports the bridge in said position. The bridge 13 has a portion in the center of its front part cut away, affording sufficient space for the feet of a person wishing to urinate only, not sitting down on the seat. If a person wishes to use the seat, he has to step on the two ends of the bridge, whereby the same will be pressed down and the mechanism connected therewith will raise the two covers 6 off the seat-sections, as is obvious from the drawing. The springs contained in the hinges 7 will cause the covers to shut down again when the bridge will be relieved of the weight of the person standing on same, the weight of the bridge itself being lifted by the springs 14.

It is understood that while we have thus shown and described the preferred form of our invention, we do not want to be limited to its mechanical details, but may resort to such alterations and modifications which come within the scope of the claims hereunto appended.

Having thus described our invention, what we claim is:

1. The combination with paper covered toilet seats comprising two separate seat sections, of laterally opening covers secured to said seat sections, adapted to protect the paper covering on said seat sections while leaving uncovered the space comprised between the inner edges of said seat sections, substantially as and for the purpose set forth.

2. The combination with paper covered toilet seats comprising two separate seat sections connected at their fore ends, of laterally opening covers adapted to protect the paper covering on said seat sections while leaving the space comprised between the inner edges of said seat sections uncovered, and treadle-controlled means for opening said covers.

3. The combination with paper covered toilet seats comprising two separate seat sec-

tions hinged to a toilet bowl and connected at their fore ends, of laterally opening covers substantially of the shape of said seat sections, hingedly attached to the outer edges thereof and adapted to protect said paper covering while leaving the bowl accessible, treadle-controlled means for opening said covers and resilient means for automatically closing said covers on the release of said

treadle, substantially as and for the purpose 10 set forth.

JOHN SIVÁK.
ALEXANDER NAGY.
LADISLAUS BANDURAY.
